UNITED STATES PATENT OFFICE

1,931,170

BARREL PAINTING MACHINE

Fred C. Stoll, Vancouver, Wash.

Application July 22, 1930. Serial No. 469,696

1 Claim. (Cl. 91—44)

My invention is primarily intended for use in the painting of barrels, casks, and other cylindrical, oval or spherical objects.

Heretofore it has been the general custom in the painting of such objects to apply the coating by hand, and to stand the same on end, or to rotate the same past the painter by hand methods and to apply the paint with a brush or swab.

Through the use of my new and improved device, where but few barrels, or casks, or other objects are to be painted, the paint coating may be applied by a brush, broom or swab and the barrel, or cask, to be painted, or coated, is automatically rotated at the desired predeterminable speed by the painter in order to speed up the work and to apply the desired coat.

Where relatively large numbers of barrels, or casks, are to be painted, or coated, the painting coat may be applied pneumatically or by a spray application. The barrel or cask being rotated at a predeterminable rate of speed to properly coat the same. Means are provided in my new and improved machine for the applying of different colors of material to different parts of the barrel or cask and to apply the same simultaneously. Where second hand barrels, or casks, are to be treated, or where the outside has deteriorated for any reason, and where a relatively heavy coat is to be applied, or where the coat is to be applied from relatively thick material, or material having a high viscosity, the material may be spread on and brushed in as a simultaneous operation.

The invention in its preferred embodiment, consists of a frame, having a plurality of power driven supports upon which the object to be painted or coated is supported and by which the same is rotated. The supports are power driven and are arranged to rotate a barrel, or cask, or object, at the desired speed to apply the coating material at the most advantageous speed. Manually settable means are associated therewith for predetermining the rate of speed at which the object to be painted is to be rotated. Paint receptacles are disposed at either side of the machine, and at one end, in which the coating material is placed and from which the material is drawn either for hand application or for power application.

An agitator is disposed in each of the paint receptacles for maintaining the coating material in a desired state of mix. Means are provided for the ejecting of the painted object from the machine and for the delivery of the same upon the machine, by gravity.

The primary object of my invention is to provide automatic means for the painting of objects such as barrels, casks, and any and all cylindrical, spherical and other shapes having a circular cross sectional area.

A still further object of my invention consists in providing power means for the painting and coating of objects where the same are to be handled continuously and in commercial quantities.

And still further objects of my invention consist in providing a painting device that is adapted for power, or hand use.

And still further objects of my invention consist in providing a simply and inexpensively constructed machine that may be used over relatively long periods for the painting and coating of objects, in commercial quantities, in which a minimum of labor cost, and freedom from alteration and repair are required.

With these and incidental objects in view, the invention consists in certain novel features of construction and combination of parts, the essential elements of which are set forth in the appended claims, and a preferred form of embodiment of which is hereinafter shown with reference to the drawings which accompany and form a part of this specification.

Fig. 1 is a top, plan view of my assembled device.

Fig. 2 is a sectional, side view of the assembled device, the same being taken on line 2—2 of Fig. 1 looking in the direction indicated.

Fig. 3 is a sectional, end view of the assembled device, the same being taken on line 3—3 of Fig. 2 looking in the direction indicated.

Fig. 4 is a side view of the assembled device.

Fig. 5 is a plan view of a modified form of my device made to show the application of the coating, as by spraying, to the heads of a barrel and to the outside of the staves as a simultaneous operation in which the application of different colors may be applied to the exterior of the barrel as a simultaneous operation.

Fig. 6 is a sectional, side view of the mechanism illustrated in Fig. 5.

Like reference characters refer to like parts throughout the several views.

I preferably form my new and improved device of a fabricated frame 1. A prime mover 2 is associated with the frame, the prime mover being adapted to coact with a speed reducer 3. A gear box 4 is provided within the frame having a set of interchangeable gears disposed therein that are adapted for hand manipulation.

through any suitable means, as by a lever 5, for changing the speed from low to high, and to medium. By the placing of the lever 5 into the position as illustrated at L, a low speed would be obtained. Whereas by placing the lever in position as illustrated in full line view in Fig. 4, and in registerable alignment with the letter M, a medium speed would result whereas by the placing of the lever indicated in position H, a high speed would be produced. I do not lay any particular claim to the speed reducing or speed changing mechanism as there are many devices that may be used to produce the desired result.

Shafts 6 and 7 are disposed transversely of the frame and are journaled within suitable bearings 8, 9, 10 and 11 that are disposed upon the frame. The shafts are driven by any suitable driving mechanism as by a sprocket 12 that is placed upon a shaft extending outward from 20 and being disposed through the gear box 4. The sprocket has a chain 13 trained thereabout that acts as a driving chain. A second sprocket 14 is disposed upon the shaft 6 and a chain 15 coacts therewith that passes about the sprocket 16 disposed upon the shaft 7 and thereby drives the supporting wheels 17 and 18 mounted upon the shafts and upon which the barrel, cask, or other object to be painted, rests. The rotating of the supporting wheels causes the object, to be painted, to be rotated. I have found best results are obtained wherein the supporting mechanism for the object to be painted is toothed upon its outer periphery to thereby cause the object to be painted to rotate as the supporting wheels, or 35 toothed members are rotated.

Vats 19 and 20 are disposed at the oppositely disposed sides of the frame into which the coating material is placed. A third shaft 21 is disposed transversely of the frame and is journaled within suitable bearings disposed within the frame members. Agitating heads 22 and 23 are disposed upon the oppositely disposed ends of the shaft 21 and as the shaft 21 is rotated the agitating heads are rocked.

45. A pitman 24 is mounted upon the shaft of the gear box and a pitman rod 25 is secured to the pitman 24 upon its one end. The pitman rod is secured upon its oppositely disposed end to a crank 26 and as a rotating motion is imparted to the pitman 24 a rocking motion will be imparted to the crank 26 to thereby rock the shaft 21 and to impart a pendulum action to the agitating heads 22 and 23 to maintain the coating material in a uniform state of viscosity 55 within the respective vats 19 and 20.

A vat 27 is disposed at one end of the frame and a shaft 28 is disposed within the vat upon which an agitating head 29 is disposed. The shaft 28 is rocked through a pitman rod 30 connecting the crank 31 disposed upon the shaft 28 and the crank 32 disposed upon the shaft 21.

Power driven pumps 33 and 34 are mounted within the frame and are adapted for being driven by a driving chain 35. A discharge pipe 36 leads from the pump 33 that is connected to the base 37 of the vat 27 and the pipe 36 is directly secured to a spray head 38. Spray nozzles 39 are disposed in spaced relationship, upon one side of the spray head 38 and the spray head 38 is shaped to fit the contour of the object to be painted in order that each of the spray nozzles may be substantially the same distance from the object to be painted.

70 A brush 40 may be made to engage the outer peripheral surface of the object being painted

to remove the surplus material therefrom, the same being so placed so as to drain the surplus material back into the respective vats. The pump 34 is secured to the base of one of the paint vats by a pipe 41 and a discharge pipe 42 is secured to the discharge side of the pump 34.

80 Spray heads 43 and 44 are disposed at the oppositely disposed ends of the objects to be painted and the same are connected by suitable piping connections 42 with the pump 34. In order to adapt the spray heads 38, 43 and 44 to the various sizes of articles to be coated, suitable arrangements may be made to adjust the spray heads to the article to be coated. Spray nozzles 45 are inwardly disposed from each of the heads 43 and 44 and are properly spaced to completely coat the head, or end, of the article to be painted. In view of the fact that coating materials of different colors may be applied to the heads and to the outer peripheral surface of the object, protecting shields 46 and 47 are supported upon the frame and are made to come in close proximity to the head to prevent the deposit of the different colors being applied to the heads and the body of the object to be painted.

90 95 100 Spray heads 43 and 44 are disposed at the oppositely disposed ends of the objects to be painted and the same are connected by suitable piping connections 42 with the pump 34. In order to adapt the spray heads 38, 43 and 44 to the various sizes of articles to be coated, suitable arrangements may be made to adjust the spray heads to the article to be coated. Spray nozzles 45 are inwardly disposed from each of the heads 43 and 44 and are properly spaced to completely coat the head, or end, of the article to be painted. In view of the fact that coating materials of different colors may be applied to the heads and to the outer peripheral surface of the object, protecting shields 46 and 47 are supported upon the frame and are made to come in close proximity to the head to prevent the deposit of the different colors being applied to the heads and the body of the object to be painted.

105 Entrance railway tracks 48 are disposed upon one end of the frame over which the article to be coated may be rolled and discharge tracks 49 are disposed upon the opposite end of the frame over which the article may be rolled after the coating has been completed.

When it is found desirable to coat the surface of the object to be coated by hand, the discharge spray heads 43 and 44 and the shields 46 and 47 may be removed and the spray head 38 may be 110 also removed, at which time the coating may be carried on as a hand operation.

While the form of mechanism herein shown and described is admirably adapted to fulfil the objects primarily stated, it is to be understood 115 that it is not intended to confine the invention to the one form of embodiment herein shown and described, as it is susceptible of embodiment in various forms, all coming within the scope 120 of the claims which follow.

What I claim is:

In a device of the class described, the combination of an elongated and elevated frame, a paint holding vat extending transversely of the frame at one of its ends, a bail member rotatably mounted in said vat and adapted to agitate the contents thereof, similar vats arranged on both sides of the frame near the end carrying the said first mentioned vat, a pair of parallel shafts rotatably mounted transversely of the frame, a plurality of toothed wheels fixedly secured to and rotatable with said shafts and adapted to rotatably support an article to be painted, a prime mover mounted within the frame structure and power transmission means operatively interconnecting the prime mover with said rotatable shafts, conduits extending from said vats through power driven pumps thence upwardly to points above the frame, said conduits being 130 provided with spray nozzles, two of said conduits terminating in endless circles arranged one within the other at opposite sides of the frame and each of said circles being provided with spray nozzles, the other of said conduit terminating in 135 a laterally disposed conduit extending transversely of the frame, all of said conduits adapted to convey paint under pressure to and through the nozzles to the articles to be painted.

FRED C. STOLL. 150
